US0D1083554S

(12) **United States Design Patent** (10) **Patent No.:** **US D1,083,554 S**
(45) **Date of Patent:** ** *Jul. 15, 2025

(54) **UNIVERSAL WHEELS WITH CARRIAGE**

(71) Applicant: **Bannack Medical LLC**, Gilbert, AZ (US)

(72) Inventors: **Arlen Olsen**, Clifton Park, NY (US); **Joel Price**, Germantown, MD (US)

(73) Assignee: **BANNACK MEDICAL LLC**, Gilbert, AZ (US)

(*) Notice: This patent is subject to a terminal disclaimer.

(**) Term: **15 Years**

(21) Appl. No.: **29/813,033**

(22) Filed: **Oct. 26, 2021**

(51) LOC (15) Cl. **08-08**

(52) U.S. Cl. USPC **D8/349**

(58) **Field of Classification Search**

(57) **CLAIM**

The ornamental design for a universal wheels with carriage, as shown and described.

DESCRIPTION

FIG. 1 is a top front perspective view of a universal wheels with carriage shown in an environment of use.

FIG. 2 is a top front perspective view thereof;

FIG. 3 is a front view thereof;

FIG. 4 is a rear view thereof;

FIG. 5 is a side view thereof;

FIG. 6 is an opposite view thereof;

FIG. 7 is a top view thereof; and,

FIG. 8 is a rear view thereof.

The broken lines in the drawings depict portions of the universal wheels with carriage that form no part of the claimed design.

1 Claim, 6 Drawing Sheets
